[57] **CLAIM**

The ornamental design of a dispenser for rolls of tape or the like, as shown and described.

DESCRIPTION

FIG. 1 is a top front perspective view of a dispenser for rolls of tape or the like showing my new design; FIG. 2 is a bottom rear perspective view; FIG. 3 is a side elevational view; FIG. 4 is a view similar to FIG. 3 but with the lid partially open; and FIG. 5 is a top plan view thereof.
